CARRIER FOR JARS OR THE LIKE

Harry Perlman, 65 Fern Drive,
Roslyn, N.Y. 11576

Filed Sept. 13, 1967, Ser. No. 8,581

Term of patent 14 years

(Cl. D9—178)

Fig. 1.

Fig. 2.

Fig. 3.

Fig. 4.

FIG. 1 is a top perspective view of a carrier for jars or the like showing my new design wherein the handle emits from a triangular boss,

FIG. 2 is a top plan view thereof,

FIG. 3 is a front elevational view with the handle raised,

FIG. 4 is a similar front elevational view with the handle lowered,

FIG. 5 is a top perspective view of a modified form of the carrier for jars or the like of my new design wherein the handle is attached directly to the frame thereof,

FIG. 6 is a top plan view thereof,

FIG. 7 is a side elevational view with the handle raised, and

FIG. 8 is a similar side elevational view with the handle lowered.

I claim:

The ornamental design for a carrier for jars or the like, substantially as shown and described.
